UNITED STATES PATENT OFFICE.

JOSEPH E. GOODMAN AND LOUIS GOODMAN, OF STOCKTON, CALIFORNIA.

TIRE-PROTECTOR.

1,086,523.

Specification of Letters Patent.

Patented Feb. 10, 1914.

Application filed May 16, 1912. Serial No. 696,372.

To all whom it may concern:

Be it known that we, JOSEPH E. GOODMAN and LOUIS GOODMAN, citizens of the United States, residing at Stockton, in the county of San Joaquin, State of California, have invented certain new and useful Improvements in Tire-Protectors; and we do declare the following to be a clear, full, and exact description of the same, such as will enable others skilled in the art to which it appertains to make and use the same, reference being had to the accompanying drawings, and to the characters of reference marked thereon, which form a part of this application.

This invention relates to improvements in protectors for pneumatic tires, the object of the invention being to produce a device which may be used as a part of the outer casing of a pneumatic tire or as a lining for use between the outer casing of a pneumatic tire or as a lining for use between the outer casing and the inner tube, which protector may be so constructed as to make the tire substantially puncture and blow-out proof on its tread.

A further object of the invention is to produce a protector which will be sufficiently flexible to conform itself to the resilient movement of the tire as the same rides over the road surface.

A further object of the invention is to produce a simple and inexpensive device and yet one which will be exceedingly effective for the purposes for which it is designed.

These objects we accomplish by means of such structure and relative arrangement of the parts as will fully appear by a perusal of the following specification and claim, this case being more especially intended as an improvement over the structure shown in Patent No. 1,023,733.

On the drawings similar characters of reference indicate corresponding parts in the several views.

Figure 1 is a sectional view of a casing and inner tube showing our improved device inserted between the outer casing and the inner tube. Fig. 2 is a sectional view of the improved lining. Fig. 3 is a top plan view of a portion of fabric showing the metallic disks secured thereon. Fig. 4 is a

sectional view of a piece of fabric showing one method of attaching the metallic disks thereon.

Referring now more particularly to the characters of reference on the drawings, the numeral 1 designates the outer casing and the numeral 2, the inner tube.

As before stated our improved protector will be inserted as a part of the tread of the outer casing or a lining between the outer casing and the inner tube. In this particular application, however, we have preferably shown it as a lining and hence the following description will refer to it as such.

In constructing our improved invention, we first take a piece of fabric 3 which would be preferably of a strong, coarse textile material such as canvas or the like, and to this material we will secure small metallic disks, or in fact any small metallic plates 4 disposed in rows, each disk in each row overlapping its adjacent disk and each row overlapping its adjacent row substantially as shown in Fig. 3. These disks 4 may be sewed, riveted, clamped or otherwise secured to the fabric 3 but for the purpose of illustration we have shown the same as being clamped by means of clamps 5, the lower ends of such clamps 5 projecting across each other as at 6 and having free projecting ends 7. These ends 7 will always project at a spaced distance from the fabric 3 to permit rubber to be vulcanized between them and the fabric which will act as a lock for the said rubber to the fabric. After the disks 4 are secured to the fabric 3 we

then vulcanize a lamination of rubber 8 around said disks and said fabric and then cover this rubber 8 on each side with another lamination of fabric 9 and then cover the whole with a covering of rubber 10 and then inclosing the entire structure with a fabric 11. The whole made in a substantial semi-circular manner in order to readily fit into the casing 1 and the tube 2. As will be seen this structure of the disks flexibly connected with the flexible fabric 3 will permit the same to conform to the resiliency of the casing 1 and the inner tube 2 and at the same time the disks 4 will prevent puncture and blow-out on the tread of the tire.

The structure of the fabric and of the rubber lamination as described prevents

heat and friction of the disks 4 from becoming so great as to render the device impracticable.

From the foregoing description it will be 5 readily seen that we have produced such a device as substantially fulfills the objects of the invention as set forth herein.

While this specification sets forth in detail the present and preferred construction 10 of the device, still in practice such deviations from such detail may be resorted to as do not form a departure from the spirit of the invention.

Having thus described our invention what 15 we claim as new and useful and desire to secure by Letters Patent is:

A device of the character described comprising a fabric, a plurality of metallic disks disposed in rows on said fabric each 20 disk in each row overlapping its adjacent disk and each row of disks overlapping its

adjacent row of disks, a clamp disposed through each disk and said fabric the lower ends of each clamp being bent and projecting across each other and having free projecting ends spaced a distance from said fabric, a lamination of rubber disposed around said disks and clamps and said fabric and between said free ends on said clamps and said fabric, another lamination 25 of fabric disposed around said lamination of rubber and another lamination of rubber disposed around said last named fabric, as described.

In testimony whereof we affix our signatures in presence of two witnesses.

JOSEPH E. GOODMAN.
LOUIS GOODMAN.
